UNITED STATES PATENT OFFICE.

ALBERT J. LOEPSINGER, OF EDGEWOOD, RHODE ISLAND, ASSIGNOR TO GENERAL FIRE EXTINGUISHER COMPANY, OF PROVIDENCE, RHODE ISLAND, A CORPORATION OF NEW YORK.

AUTOMATIC SPRINKLER SYSTEM.

Application filed May 19, 1917. Serial No. 169,653.

To all whom it may concern:

Be it known that I, ALBERT J. LOEPSINGER, a citizen of the United States, residing at Edgewood, in the county of Providence and 5 State of Rhode Island, have invented certain new and useful Improvements in Automatic Sprinkler Systems, of which the following is a specification.

This invention relates to automatic sprinkler systems in which the sprinkler pipes are normally filled with air maintained at a pressure which is less than the water supply pressure, but is sufficient to prevent the opening of the supply-controlling valve located at the entrance to the sprinkler pipe system. According to the common practice the air in such a system is kept at a pressure considerably in excess of that at which the valve opens, in order to guard against 10 premature opening of the valve on account of leakage of air from the system or, in the case of valves of the type usually employed, by reason of water hammer or other abnormal pressure exerted on the valve from 15 the water supply side, and consequently when one or more sprinkler heads open the valve remains closed until the excess air pressure which keeps it closed is lost by the escape of a part of the compressed air from 20 the system. This fact constitutes a well-recognized objection to dry-pipe sprinkler systems as heretofore installed, for the reason that until the valve opens the rate at 25 which the air in the sprinkler pipe system escapes therefrom is determined by its own pressure, as distinguished from the pressure of the water supply, and the resulting delay in the discharge of water from the opened head or heads may become serious in case the 30 air pressure normally maintained in the 35 sprinkler pipe system needs to be but a few pounds above atmospheric pressure, since in such case the escape of the air is correspondingly slow prior to the opening of the 40 valve.

The present invention is intended to provide a dry-pipe sprinkler system which will be free from the objection above referred to, and is characterized by the employment of 45 means whereby a slight reduction of the air pressure in the system is caused to bring into immediate action a force which neutralizes the excess or effective pressure whereby the

supply-controlling valve is normally prevented from opening, provided such reduction of pressure is a quick reduction such as results from the opening of one or more sprinkler heads, as distinguished from a slow reduction such as results from mere leakage of air. The new result obtained is 55 that although leakage of air from the system has no greater effect on the supply-controlling valve than in the ordinary dry-pipe system, the opening of the valve immediately follows the opening of one or more 60 sprinkler heads instead of being delayed until the air pressure which normally prevents the valve from opening has been reduced to a point at which it is insufficient for that 65 purpose, and consequently the interval between the opening of a sprinkler head and the opening of the valve is not dependent upon the pressure or volume of the air in the system but is practically the same for 70 all systems in which the invention is employed. 75

Various arrangements may be employed for making effective the neutralizing force above referred to, and the invention may be readily applied to systems having supply-controlling valves of any of the usual types. In dry-pipe valves of the differential type it is the practice to provide between the air valve and the water valve an intermediate chamber in which atmospheric pressure is 80 normally maintained by means of an open drip connection, and when my invention is applied to a sprinkler system containing a valve of this character the opening of the valve is preferably accomplished by admitting fluid under pressure to the intermediate chamber. When this is done the air valve is subjected to pressure on both sides, and as soon as the resultant pressure tending 85 to hold the valve closed is sufficiently reduced the entire valve is opened by the supply pressure acting on the water valve, thereby letting water into the system. The fluid under pressure which is admitted to the intermediate chamber may be taken 90 from any suitable source of supply. For example, it may consist of air taken from the sprinkler pipe system, in which case it will have the system pressure, or it may consist of water taken from the water supply 95 below the valve, in which case it will have 100 105

the service pressure. Constructions operating in both of the ways just referred to are illustrated in the accompanying drawings, in which:

- 5 Figure 1 is an elevation, partly in section, showing a portion of a sprinkler pipe system provided with means for admitting air from the system to the intermediate chamber in the valve;
- 10 Figure 2 is a vertical section on a larger scale, showing certain pressure-controlled parts hereinafter described;

Figure 3 is a section on the line $\alpha-\alpha$ in Figure 2;

- 15 Figure 4 is a section showing the details of a flow-restricting device, and
- Figure 5 is a view similar to Figure 1, illustrating a system provided with means for admitting water under pressure to the

20 intermediate chamber.

In Figures 1 and 5 of the drawings 2 indicates the lower portion of a riser, which may be assumed to form a part of a system of sprinkler pipes provided with the usual heads, and 3 indicates a dry-pipe valve interposed between the lower end of the riser 2 and the water supply pipe 4. The particular dry-pipe valve illustrated is constructed and adapted to operate in the manner shown 25 and described in U. S. Letters Patent No. 1,196,875, granted September 5, 1916, and comprises an air valve 5 carried by an arm 6 which is pivotally mounted within the valve casing, a water valve 7 carried by the air valve 5, and valve seats 8 and 9 on which the valves 5 and 7 are respectively seated under normal conditions and which are separated by an intermediate chamber 10. To this chamber is connected, as is customary in 30 dry-pipe valves, a normally-open drip attachment 11 which takes care of any leakage into the chamber 10 and is automatically closed by the pressure of the water entering the chamber when the valve opens.

45 The parts above referred to are to be regarded as representative of any dry-pipe sprinkler system in which the water supply is normally kept out of the sprinkler pipes by the action of air or other gas contained in 50 the sprinkler pipe system and having a pressure less than that of the water supply. To these parts or their equivalents is added, in the illustrated embodiments of the invention, a closed tank 12 which is connected to the 55 sprinkler pipe system by a pipe 13, whereby the tank is normally kept filled with air at the same pressure as in the sprinkler pipe system. The rate of flow of air through this pipe, however, is limited by a small orifice 60 14 through which the air has to pass and which is of such size that while it is adequate to maintain equal pressures in the sprinkler pipe system and the tank 12 in case leakage of air from the system occurs 65 it is incapable of keeping the pressures equal

in case the pressure in the system is reduced by the opening of one or more sprinkler heads. Consequently, while under static conditions the air pressures in the sprinkler pipe system and in the tank 12 are always 70 the same the opening of one or more sprinkler heads has the effect of immediately unbalancing these pressures, leaving the pressure in the tank greater than that in the sprinkler pipe system; and it is the differential pressure thus created which is utilized to effect the immediate opening of the dry-pipe valve.

In the construction illustrated in Figures 1, 2 and 3 the establishment of the differential pressure just referred to causes air under pressure to be admitted to the chamber 10 through a pipe 15 connecting the chamber to a supplementary receptacle 16 which in turn is connected to the riser 2 by a pipe 17. 80 The receptacle 16 contains a valve 18, shown as a pivoted gravity valve, which normally closes the entrance to the pipe 15, and also contains a valve-opening device preferably consisting of a pivotally mounted lever 19 85 carrying a weight 20 which is normally held by gravity against the wall of the receptacle 16 or other suitable stop, in which position the center of gravity of the weighted end of the lever is located nearly over its pivot 90 and a finger 21 constituting the lower end of the lever is located beneath the free end of the valve 18. 22 indicates a flexible diaphragm, preferably made from a sheet of soft rubber, which is interposed between 95 the interior of the receptacle 16 and a passage 23 connected to the tank 12 by a pipe 24, and 25 indicates a horizontal stem connected at one end to the diaphragm 22 and arranged in line with the upper end of the lever 19. The parts 22 and 25 normally occupy the positions shown in Figure 2, in which the diaphragm is supported in part by the adjacent wall of the receptacle 16 and in part by a perforated plate 26 through 100 which the diaphragm is subjected to air pressure transmitted through the pipe 24, and when in this position the free end of the stem 25 is located at a short distance from the lever 19. 27 indicates a perforated plate 105 carried by the receptacle 16 in front of the diaphragm 22 and serving as a stop and support for the diaphragm when forced inward by the air pressure transmitted through the pipe 24, and 28 indicates a central sleeve 110 carried by the plate 27 and provided with guides 29 for the stem 25.

Assuming that the water supply has been shut off and the dry pipe valve closed the parts above described are put in condition 115 for operation by opening the receptacle 16, which is composed of separable portions, as shown, locating the valve-opening lever 19 in its upright position and closing the valve 18, closing the receptacle 16, and then pump- 120 130

ing air into the sprinkler pipe system until the normal pressure is established therein. As the air pressure in the system increases it is increased at the same rate in the receptacle 16 through the pipe 17, and it also increases in the tank 12 but more slowly, since the air entering the tank has to pass through the restricted orifice 14. Consequently the pressure exerted on the dia-
 phragm 22 from within the receptacle 16 is greater than that exerted on the opposite side of the diaphragm, so that it is impossible for the latter to move while the normal air pressure is being established, but after this has been done the pressure is soon equalized in the tank 12 by the flow of air through the orifice 14. If the water supply is then turned on below the dry pipe valve the system is put in its normal or static condition, the dry pipe valve being held closed by the air pressure, and so long as this condition exists the tank 12 and receptacle 16 remain filled with air at the same pressure as that in the sprinkler pipe system, the valve 18 is held closed by gravity supplemented by the air pressure in the receptacle 16, the diaphragm 22 is subjected to equal pressures on both sides and remains in the position shown in Figure 2, and atmospheric pressure is maintained in the chamber 10 by means of the open drip 11. In case leakage of air from the sprinkler pipe system occurs the air pressures in the tank 12 and receptacle 16 are diminished at the same rate; so that the diaphragm 22 has no tendency to move and the valve 18 remains closed, but if one or more sprinkler heads open, the air pressure in the sprinkler pipe system and consequently in the receptacle 16 is reduced more rapidly than in the tank 12, on account of the effect of the orifice 14 on the flow of air from said tank to the pipe 13, and hence the reduction of air pressure within the receptacle 16 causes the diaphragm 22 to be subjected to a differential pressure whereby it is caused to tip the lever 19 and thereby open the valve 18 in an obvious manner. Air under pressure then passes from the receptacle 16 to the chamber 10 and the pressure thus established in said chamber closes the drip 11 and also balances the pressure on the system side of the air valve 5, with the result that the dry pipe valve is instantly opened by the water supply pressure acting on the water valve.

The arrangement above described for opening the valve 18 has the advantage that although a slight differential pressure acting on the diaphragm 22 will suffice to move the weighted lever 19 past its dead-center position, the kinetic energy developed by the falling weight 20 will provide ample force for opening the valve 18 against the fluid pressure to which it is subjected, so that any

tendency of the valve to stick will be effectively overcome.

The orifice 14 is shown as formed in the inner end of a plug 30 screwed into a casing 31 which is interposed between the tank 12 and the pipe 13 and is divided internally into two separate chambers 32 and 33. The inner portion of the plug 30, which enters the chamber 32, is made hollow and provided with lateral perforations 34 so located that when the plug is in place they communicate with an annular groove 35 connected by a passage 36 with the chamber 33, the capacity of the several passages to transmit air being determined by the size of the orifice 14. With this arrangement, the plug 30 can be conveniently removed for the purpose of inspecting the condition of the orifice 14 and cleaning it in case it has become clogged by dirt blown into it from the sprinkler pipe system when the apparatus is charged with compressed air. In order to minimize the danger of clogging the orifice 14 the chamber 33 is preferably divided by a strainer 37 contained therein, through which the air has to pass before it reaches the plug 30.

The construction illustrated in Figure 5 is similar to that already described except that the receptacle 16' is connected by a pipe 17' to the water supply pipe 4 and hence is normally kept filled with water at the supply pressure, which is admitted through the pipe 15' to the intermediate chamber 10 when the normally-closed gravity valve 18' is opened. In this case, since the water supply pressure is different from the normal pressure in the sprinkler pipe system, the means employed for opening said valve 18' are modified by providing in the receptacle 16' two pressure-operated devices 38 and 39 each of which consists substantially of a bellows having the form of a closed cylinder made of thin sheet metal and deeply corrugated circumferentially, so that it is adapted to lengthen or shorten whenever it is subjected internally and externally to a differential pressure. These devices 38 and 39, which are arranged horizontally in line with each other, are connected internally by pipes 40 and 41 to the riser 2 and the tank 12 respectively, and at their adjacent ends they are connected to each other, without communicating, by a rigid bar 42 having a downwardly-extending portion, against which the weighted upper end of the valve-opening lever 19' rests when the parts are in their normal position. While the air pressure in the sprinkler pipe system is being pumped up the pressure within the bellows 38 will slightly exceed that within the bellows 39 and hence the bar 42 will be moved somewhat to the right with reference to the normal position shown in Figure 5, but since such movement is in the direction towards which the weight-

ed upper end of the lever 19' tends to move under the action of gravity said lever will merely follow the bar and will ultimately be restored to the normal position illustrated when the pressure in the tank 12 becomes equal to that in the sprinkler pipe system, and no change in the position of the bar 42 will occur when the water supply is turned on and enters the receptacle 16' because the water pressure will act equally on the exterior of both of the bellows 38 and 39. A slow reduction of pressure in the sprinkler pipe system will evidently have no effect on the bar 42, because the pressures within the bellows 38 and 39 will diminish equally, but a quick reduction of pressure due to the opening of one or more sprinkler heads will cause the pressure within the bellows 38 to fall more rapidly than the pressure within the bellows 39, on account of the effect of the restricted orifice above described, and consequently the bar 42 will move in such direction as to carry the lever 19' past its dead center position and cause it to open the valve 18', whereupon the water pressure established in the chamber 10 through the pipe 15' will close the drip 11 and overbalance the pressure on the system side of the air valve 5, resulting in the instant opening of the dry pipe valve.

Each of the illustrated embodiments of my invention has the advantage that the new parts employed constitute an attachment which can be readily added to an existing sprinkler system containing a dry pipe valve of the differential type without otherwise altering the system or valve in any respect. It will be understood, however, that the invention is not limited to such an attachment and that it may be utilized for effecting the opening of any sort of dry pipe valve normally held closed by fluid pressure maintained in the sprinkler pipe system, the means employed for this purpose being capable of modification in various ways.

The modification of my invention illustrated in Figure 5 of the drawings is not specifically claimed herein, as it forms the subject matter of a divisional application filed on the 26th day of November, 1923, Serial No. 676,951.

I claim:

1. In an automatic sprinkler system, the combination of a dry-pipe valve normally held closed by fluid pressure in the system, and means rendered operative by a quick reduction but not by a slow reduction of the system pressure, for subjecting the valve to an opening force acting in opposition to said pressure.

2. In an automatic sprinkler system, the combination of a dry-pipe valve normally held closed by fluid pressure in the system, a movable member subjected to normally-balanced fluid pressures acting in opposite

directions thereon, means for causing the opening of one or more sprinkler heads to unbalance the pressures on said movable member, and means operated by said movable member for subjecting the valve to an opening force acting in opposition to the system pressure.

3. In an automatic sprinkler system, the combination of a dry-pipe valve normally held closed by fluid pressure in the system, a fluid-pressure receptacle and connections between it and the sprinkler pipe system whereby the system pressure is normally maintained in said receptacle, flow-restricting means included in said connections, a movable member subjected simultaneously to the pressures in the sprinkler pipe system and the receptacle and operable by a difference in said pressures, and means operated by said movable member for subjecting the valve to an opening force acting in opposition to the system pressure.

4. In an automatic sprinkler system, the combination of a dry-pipe valve normally held closed by fluid pressure and comprising an air valve, a water valve and an intermediate chamber, and means rendered operative by a quick reduction but not by a slow reduction of the system pressure for increasing the pressure in said chamber while the water valve is closed and thereby causing it to open.

5. In an automatic sprinkler system, the combination of a dry-pipe valve normally held closed by fluid pressure and comprising an air valve, a water valve and an intermediate chamber provided with a normally-open drip valve, and means operative upon the opening of one or more sprinkler heads for admitting fluid under pressure to said chamber while the water valve is closed and thereby causing it to open.

6. In an automatic sprinkler system, the combination of a dry-pipe valve normally held closed by fluid pressure and comprising an air valve, a water valve and an intermediate chamber, connections between said chamber and a supply of fluid under pressure, a valve normally closing said connections, and means rendered operative by a quick reduction but not by a slow reduction of the system pressure for opening the last-mentioned valve.

7. In an automatic sprinkler system, the combination of a dry-pipe valve normally held closed by fluid pressure and comprising an air valve, a water valve and an intermediate chamber, connections between said chamber and a supply of fluid under pressure, a valve normally closing said connections, a movable member subjected to normally-balanced fluid pressures acting in opposite directions thereon, means operative upon the opening of one or more sprinkler heads for unbalancing the pressures on said

movable member, and means operated by said movable member for opening the last-mentioned valve.

8. In an automatic sprinkler system, the combination of a dry-pipe valve normally held closed by fluid pressure and comprising an air valve, a water valve and an intermediate chamber, a fluid pressure receptacle connected to the sprinkler pipe system, flow-restricting means included in said connections, a movable member subjected simultaneously to the pressures in the sprinkler pipe system and the receptacle and operable by a difference in said pressures, connections between said intermediate chamber and the sprinkler pipe system, a valve normally closing the latter connections, and means operated by said movable member for opening the last-mentioned valve.

9. In an automatic sprinkler system, the combination with a dry-pipe valve of means for causing it to open, comprising a receptacle containing fluid under pressure and provided with an outlet, a valve normally closing said outlet, a weighted arm normally maintained in elevated position and arranged to open the latter valve when it falls, and means rendered operative by the opening of one or more sprinkler heads for causing said weighted arm to fall.

10. In an automatic sprinkler system, the combination with a dry-pipe valve of means for causing it to open, comprising a passage extending from one side of the valve to its intermediate chamber, a valve normally closing said passage, a weight normally maintained in elevated position and arranged to open the latter valve when it falls, and means responsive to change of pressure resulting from the opening of one or more sprinkler heads for causing said weight to fall.

11. In an automatic sprinkler system, the combination of a dry-pipe valve normally held closed by fluid pressure and comprising an air valve, a water valve and an intermediate chamber, connections between said intermediate chamber and a supply of fluid under pressure, a valve normally closing said connections, a weighted arm normally maintained in elevated position and arranged to open the last-mentioned valve when it falls, and means rendered operative by the opening of one or more sprinkler heads for causing said weighted arm to fall.

12. In an automatic sprinkler system, the combination of a dry-pipe valve normally held closed by fluid pressure and comprising an air valve, a water valve and an intermediate chamber, connections between said intermediate chamber and a supply of fluid

under pressure, a valve normally closing said connections, a weighted arm normally maintained in elevated position and arranged to open the last-mentioned valve when it falls, a movable member adapted to tip said arm and subjected to normally-balanced fluid pressures acting in opposite directions thereon, and means operative upon the opening of one or more sprinkler heads for unbalancing the pressures on said movable member.

13. In an automatic sprinkler system, the combination of a dry-pipe valve normally held closed by fluid pressure and comprising an air valve, a water valve and an intermediate chamber, a receptacle connected to the sprinkler pipe system, connections between said receptacle and intermediate chamber, a valve normally closing the latter connections, a movable member subjected on one side to the pressure in the receptacle and on the other side to the system pressure through connections including a restricted opening, and a weighted arm normally maintained in elevated position and arranged to open the last-mentioned valve when it falls, said arm being located in position to be operated by said movable member when the pressure in said receptacle is reduced by the opening of one or more sprinkler heads.

14. An attachment for automatic sprinkler systems, comprising a fluid pressure receptacle, means for connecting it to a sprinkler pipe system and permitting a restricted flow of fluid under pressure from the system to the receptacle, a supplementary receptacle adapted to be connected to a supply of fluid under pressure, pipe connections leading from the latter receptacle, a valve normally closing said pipe connections, a movable member located in the supplementary receptacle and operable by a difference in pressures between the sprinkler pipe system and the first-mentioned receptacle, and means operated by said movable member for opening said valve.

15. An attachment for automatic sprinkler systems, comprising connections providing a passage for fluid under pressure, a valve normally closing said passage, a movable member and connections for subjecting it to the action of normally-balanced fluid pressures, flow-restricting means included in one of said connections, and means operated by the movable member for opening said valve.

Signed at Boston, Massachusetts, this 18th day of May, 1917.

ALBERT J. LOEPSINGER.
